(57) **CLAIM**

We claim the ornamental design for a pipe coupling segment, as shown and described.

DESCRIPTION

FIG. 1 is an isometric view of our design for a pipe coupling segment;

FIG. 2 is a top view of pipe coupling segment shown in FIG. 1;

FIG. 3 is a bottom view the pipe coupling segment shown in FIG. 1;

FIG. 4 is a front view of the pipe coupling segment shown in FIG. 1, the rear view being a mirror image thereof;

FIG. 5 is a right end view of the pipe coupling segment shown in FIG. 1; and,

FIG. 6 is a left end view the pipe coupling segment shown in FIG. 1.

The broken lines depict portions of the pipe coupling segment that form no part of the claim.

1 Claim, 3 Drawing Sheets
